2,465,031

FLUORESCENT TUBE LIGHTING SYSTEM

Max Nathanson, Montreal, Quebec, Canada

Original application August 8, 1946, Serial No. 692,906, now Patent No. 2,436,399, issued February 24, 1948. Divided and this application August 23, 1947, Serial No. 770,304

2 Claims. (Cl. 315—255)

1

This invention relates to fluorescent tube lighting systems and the object is to provide improved means for operating a plurality of fluorescent tubes in series with each other at a voltage substantially lower than the sum of the breakdown voltages of the individual tubes.

The present invention is a division of my pending application Serial No. 692,906, filed August 8, 1946, which issued February 24, 1948 as U. S. Patent No. 2,436,399.

Proceeding now to a more detailed description of my invention, reference will be had to the accompanying drawings, in which—

Fig. 1 is a diagrammatic elevational view of a transformer and other component elements of a fluorescent tube lighting system embodying my invention.

Fig. 2 is a wiring diagram of the system shown in Fig. 1.

Fig. 3 is a view similar to Fig. 1 but showing a slight modification.

Fig. 4 is a wiring diagram of the system shown in Fig. 3.

Figs. 1 and 2 illustrate a three-tube system wherein inductance coils are used to operate two of the tubes in series on what is hereinafter termed "the inductive side of the system."

The transformer generally indicated at 59 in Figs. 1 and 2 is shown as a high leakage reactance shell-type transformer comprising a primary coil 60 and three secondary coils 61, 62 and 63. The four coils are arranged in side by side relation on a central core leg 64 lying between and parallel with outer legs 65 and 66, all of said legs being joined to end pieces 67 and 68. Coils 60 and 61 are arranged on leg 64 at one side of high leakage reactance magnetic shunts 69. The remaining coils 62 and 63 are arranged on leg 64 at the opposite side of said shunts.

On what may be termed the condensive side of the system shown in Figs. 1 and 2 a fluorescent tube 71 is connected across coils 60 and 61 in series with a current-limiting condenser 72. In tracing the circuit connections of tube 71, as illustrated in Fig. 2, it will be noted that primary coil 60 is connected across an alternating current potential source 73 by leads 74 and 75. The left hand end of coil 60 is connected at junction 76 to the right hand end of coil 61. The left hand end of coil 61 is connected to the transformer side of condenser 72 by lead 77. The tube side of condenser 72 is connected to the left hand electrode of tube 71 by lead 78. The right hand electrode of tube 71 is connected to the right hand end of coil 60 by lead 79. The condenser 72 is charged

2

by the high voltage secondary coil 61 and serves as a current limiting device for the current which is supplied to tube 71 to establish an ionized, conductive, and luminescent condition of said tube.

On what may be termed the inductive side of the system shown in Figs. 1 and 2, a pair of fluorescent tubes 81 and 82 are connected in series with each other across the coils 60 and 62 by circuit connections which may be traced as follows:

The left hand end of coil 62 is connected by lead 83 to the left hand end of coil 60 at junction 76. The right hand end of coil 62 is connected by lead 84 to the left hand electrode of tube 82. The right hand electrode of tube 82 is connected to the right hand electrode of tube 81 by lead 85. The left hand electrode of tube 81 is connected to the right hand end of coil 60 by lead 86 joining lead 79 at junction 87.

The left hand end of coil 63 is connected to the right hand end of coil 62 at junction 88. The right hand end of coil 63 is connected to the right hand electrode of tube 81 by lead 89 joining lead 85 at junction 90.

From the foregoing description of the tube connections on the inductive side of the system shown in Fig. 1 and Fig. 2, it will be apparent that tubes 81 and 82 are connected in series across the coils 60 and 62 by way of series-leads 84, 85, 86 and 79. Coil 63 is a high impedance coil which, when connected as herein described, provides a high-impedance current-limiting bypass through which a limited amount of current is shunted around tube 82 to initially establish an ionized and conductive condition of tube 81. The impedance of tube 81 is thus reduced to a value at which the voltage drop across said tube is extremely low in comparison with the voltage initially required to establish an ionized and conductive condition of said tube. When an ionized and conductive condition is established in tube 81 by the small amount of ionizing current supplied to this tube by way of by-pass coil 63, the voltage available across coils 61 and 62 is immediately effective to establish an ionized and conductive condition of tube 82 and to cause sufficient current flow through the series connected tubes 82 and 81 to establish and maintain in both of said tubes the current density required for satisfactory operation. In this connection it may be explained that coil 62 is a high inductance coil which serves, in conjunction with the magnetic shunts 69, to limit the operating current in the series connected tubes 82 and 81 to practical de-

sign limits.

The system shown in Figs. 3 and 4 is similar to that shown in Figures 1 and 2 with the exception of a modification of the circuit connections of the coils 62 and 63 and the series connected tubes 81 and 82.

Referring more particularly to Fig. 4, it will be noted that the left hand end of coil 62 is connected, by lead 83, to the left hand end of coil 60 at junction 76 and that the left hand end of coil 63 is also connected to lead 83 at junction 91. The right hand end of coil 62 is connected to the right hand electrode of tube 82 by lead 92. The left hand electrode of tube 82 is connected to the left hand electrode of tube 81 by lead 93. The right hand electrode of tube 81 is connected to the right hand end of coil 60 by lead 94 which joins lead 79 at junction 87. The right hand end of coil 63 is connected to the left hand electrode of tube 81 by lead 95 which joins lead 93 at junction 96.

In the system shown in Figs. 3 and 4, a high voltage is impressed on tube 81 through coil 63 which is wound directly on coil 62 and sufficient bleeder current flows through coil 63 to establish an ionized and conductive condition of tube 81. When tube 81 is ignited, the reactance of coil 63 limits the current in said tube to a value just sufficient to maintain ionization and current flow. The resulting drop in the impedance of tube 81 enables the voltage generated in coil 62 to establish an ionized and conductive condition in tube 82 and to cause sufficient current flow through both of the series connected tubes 82 and 81 to establish and maintain in both of said tubes the current density required for satisfactory operation. The coils 62 and 63 shown in Figs. 3 and 4 are designed so that they are effective, in conjunction with shunts 69, to limit the operating current in tubes 82 and 81 to the proper value.

Both of the systems described herein provide feasible arrangements for effecting instantaneous starting and operation of series-connected fluorescent tubes without employing operating voltages in excess of the sum of the break-down voltages of the individual tubes.

Having thus described the nature of my invention and several embodiments thereof, it will

be understood that various modifications may be resorted to within the scope and spirit of the invention as defined by the appended claims.

What I claim is:

- 5 1. In a fluorescent tube lighting system, a transformer including a central core leg and two outer core legs joined by end pieces, a primary and two secondary coils connected together in auto-transformer relationship and arranged in 10 side by side relationship on the central core leg with the primary coil lying between the secondary coils, and magnetic core shunts of high reluctance separating the primary coil and one of said secondary coils, two fluorescent tubes 15 connected in series with each other across the primary coil and the last mentioned secondary coil, means, including a high impedance coil directly connected to said last mentioned secondary coil and to the connection between the two 20 tubes, affording a current-limiting by-pass through which a relatively small amount of current is by-passed around one of said series-connected tubes to establish an ionized and conductive condition of the remaining series-connected tube and thereby enable both of said tubes to be operated in series at a voltage substantially lower than would be required in the absence of said by-pass means, and an additional tube connected across the primary coil 25 and the other secondary coil in series with a current-limiting condenser.

2. A fluorescent tube lighting system as set forth in claim 1 in which said high impedance coil is wound directly on the secondary coil 30 serving said series-connected tubes.

MAX NATHANSON.
